UNITED STATES PATENT OFFICE.

THOMAS J. STEARNS, OF BOSTON, MASSACHUSETTS, ASSIGNOR TO ROXBURY CARPET COMPANY, OF SAME PLACE.

DESIGN FOR CARPET.

Specification forming part of Design No. **11,367**, dated August 26, 1879; application filed August 1, 1879.
[Term of patent 3½ years.]

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photograph, forming a part of this specification.

The design consists in a scenic ground having representations of distant ports A, castles B C, and irregular Grecian borders E.

The design also consists in four different groups of root-work, 1 2 3 4, interwoven with flowers and vines. Said groups are arranged

upon the scenic ground and cover portions of the designs A B C E.

I claim—

The scenic ground and the four groups resting thereon, substantially as shown, as a design for a carpet.

In testimony whereof I have signed my name to this specification in the presence of two subscribing witnesses this 24th day of July, 1879.

THOMAS J. STEARNS.
